UNITED STATES PATENT OFFICE.

EDGAR H. SHELDON, OF MUSKEGON, MICHIGAN.

TABLE AND LIKE ARTICLE.

1,408,226.

Specification of Letters Patent. Patented Feb. 28, 1922.

Application filed March 5, 1920. Serial No. 363,430.

To all whom it may concern:

Be it known that I, EDGAR H. SHELDON, a citizen of the United States, residing at Muskegon, in the county of Muskegon and 5 State of Michigan, have invented a certain new and useful Improvement in Tables and like Articles, of which the following is a full, clear, concise, and exact description, reference being had to the accompanying drawings, forming a part of this specification.

My invention relates to tables and like articles, and particularly to wooden tables.

One of the objects of the invention is to provide a practical and satisfactory construction of device such as specified and particularly to provide a practical and effective construction of top for wooden tables and the like.

Another object of the invention is to provide a reenforcing construction for wooden table tops which will close any cracks that may occur on account of shrinkage of the wood, and will also secure sufficient flexibility to compensate for any expansion and contraction that may occur in the table top.

Another object of the invention is to secure simplicity of operation and cheapness of construction.

Other objects of the invention will appear 30 and be pointed out hereinafter.

In the accompanying drawings Fig. 1 is a plan view of a portion of a top for wooden tables having a reenforcing construction embodying my present invention;

Fig. 2 is a cross section taken on line 2—2 in Fig. 1;

Fig. 3 is a view of a detail of construction.

Referring to the drawings I show a table having a body portion 1 and a top 2. The 40 top 2 is composed of a plurality of pieces or strips of material 3—3 and 4—4, the strips 3—3 being at the opposite ends of the top and the strips 4—4 between the same.

The form of table may of course be varied. 45 The form shown is substantially rectangular, the strips 3—3 and 4—4 being arranged crosswise and side by side.

A reenforcing member preferably in the form of a bolt or rod is arranged crosswise 50 of the strips 3—3 and 4—4 and passed through apertures in the same so as to form a continuous reenforcing member passing through all of the intermediate strips 4—4 and terminating at the end strips 3—3. At 55 one end of the bolt or rod 5 is a head 6 and

the other end is screw threaded as at 7 and provided with a nut 8. Preferably at each end of the member 5 there are provided resilient compensating devices 10—10 preferably in the form of steel washers, one being 60 interposed between the head 6 and that portion of the strip 3 against which the head 6 acts and the other washer 10 being interposed between the nut 8 and the portion of the other strip 3 on which said nut acts. 65 These steel washers 10—10 are preferably made of spring steel and of a more or less bow-shape, as shown in Fig. 1, so that when the nut 8 is tightened and said nut and the head 6 draw up said washers 10—10, the 70 same will yield somewhat but will offer sufficient resistance to insure the strips 3—3 and 4—4 being drawn tightly together so as to make close joints between them. The upper edges of the washers are preferably arcuate, 75 as shown in Figure 3. There is also sufficient springiness or resiliency in said members 10—10 to push or draw said strips 3—3 and 4—4 together in case there should be any contraction on the part of any one of 80 said strips or in case a crack should open in any one of the same, and said members 10—10 also have sufficient resiliency to permit sufficient expansion on the part of the members 3—3 and 4—4 to compensate for 85 any enlargement or expansion which might take place due to a moist atmosphere or for other reasons. Thus a tight and even table top without cracks or crevices either between the constituent members or in any one of the 90 same is provided and assured, and at the same time enlargement or expansion of the members composing the top or any one of them is also provided for.

The head 6 of the member 5 and the nut 95 8 at the other end of the same and the washers or members 10—10 are preferably arranged in recesses or apertures 11 and 12, respectively, formed in the under side of the end members 3—3. These recesses have 100 arcuate walls conforming to the shape of the upper edges of the washers, thus preventing rotation of the latter. This permits ready access to the said members 10—10 and to the nut 8 for tightening the latter. For tightening purposes a wrench 13 is preferably provided and this may be used by inserting it into the aperture 12 from underneath.

The cross apertures 14 in the members 3 extend only to the apertures 11 and 12, leav- 110

ing the outer faces of the members 3 undisturbed. The cross aperture in one of the members 3 extends to the under face thereof, thereby making the recess 11 substantially 5 ³⁵ T-shaped so that the head end of the bolt may be positioned therein.

The member 5 may be placed in position by pushing it through in the cross apertures or holes 14 provided in the members 3—3 and 10 4—4 and then the members 10—10 may be adjusted against the inner walls of the recesses 11 and 12, respectively, and then the nut 8 tightened sufficiently to subject the members 10—10 to the proper tension.

15 The washers provide bearing surfaces for the bolt head and nut as large as the head and nut themselves, and thus substantial and even heavy strains may be effectively taken. The nut may be readily adjusted so as to 20 vary the pressure on the top members 4, 4 as desired. This pressure sometimes has to be very considerable in order to close cracks in said members; but the bolt or rod and washers sustain such pressure, and the cracks 25 are effectively closed and held closed.

Adjustment of the nut may take place at any time, either before the table has been delivered to the user or afterward. It is not necessary to remove any part of the table to 30 get access to the nut, nor is the nut, or in fact any part of the reenforcing arrangement,

visible when looking at the table in the ordinary manner.

The table top may be easily disassembled by unscrewing the bolt 8 and separating the members 3—3 and 4—4 from one another.

It will be understood that changes and modifications may be made without departing from the spirit of the invention.

What I claim is:

40 A table provided with a top composed of a plurality of strips in combination with a bolt extending transversely through alined apertures in said strips, the endmost of said strips having vertical elongated recesses 45 communicating with said apertures and provided with arcuate top walls, one of said recesses being substantially T-shaped, said bolt having a head on one end and nut threaded on the other end arranged in said vertical 50 recesses, and elongated bow-shaped spring washers in said recesses between the head and nut and the material of the adjacent strips, said washers having substantially flat medial and end bearing portions, and each 55 having an arcuate edge engaging the arcuate top walls of said vertical recesses.

In witness whereof, I hereunto subscribe my name this 26th day of January, A. D. 1920.

EDGAR H. SHELDON.
